RUG

Robert E. Walliser, Libertyville, Ill., assignor of one-third to Thor S. Johnson, Irvington, N. Y., as trustee, and one-third to William F. Stahl and one-third to Arthur Hanisch, both of Chicago, Ill.

Application January 8, 1943, Serial No. 471,671

6 Claims. (Cl. 139—402)

This invention relates to a rug, and more particularly to a rug in which the upper body or pile is formed by soft bulky pile warp threads which are integrally formed with and extend upwardly from the fabric.

An object of the invention is to provide a rug having soft bulky pile warp threads extending upwardly from the fabric, preferably in the form of long twisted loops, the loops providing a pleasing appearance and resembling what is known as bullion fringe. Another object is to provide a rug formed by a modified weaving operation wherein the soft bulky pile warp threads are spaced apart by a substantial distance within the fabric of the rug and are formed in such a manner as to be tightly secured to the body of the rug to provide a sturdy and attractive product more pleasing in appearance than rugs of this type which have heretofore been formed. Still another object of the invention is to provide a bullion twisted form of rug in which the long loops are formed integrally with the rug body, a modification of the weaving operation being employed for securely locking the loops against being pulled out of place.

Another object of the invention is to provide a rug having soft bulky pile warp threads extending upwardly from the body of the rug and spaced apart by a substantial distance, while at the same time avoiding the difficulty known as "grinning" wherein a sharp line of separation or demarcation appears between the pile warp threads in a rug when the rug is folded or bent as, for example, when the rug is used as a stair carpet. Another object is to provide in a rug, pile warp threads having upwardly-extending loops, each of the loops in one of the pile warp threads being spaced apart by a plurality of weft threads and the loops in adjacent pile warp threads being disposed between different weft threads and thus arranged in staggered relation with respect to each other rather than in straight transverse rows. A further object is to provide a rug having long twisted loops of pile warp threads extending upwardly from the fabric thereof wherein the tension on the pile warp threads in the weaving operation may be relatively great and a smooth rug surface for the fabric backing of the rug is provided. Yet another object is to provide a rug construction wherein the long twisted loops forming the upper body of the rug are drawn from the fabric in different groups, only a portion of the loops being formed in a single picking operation.

In the prior art efforts to form a rug of the

5 bullion twist type, it has been the practice to form the long twisted loops separately and to stitch them to a woven fabric base in order to adequately secure the loops to the base. Obviously, such an operation is laborious and expensive, and the product lacks the smooth regularity and uniformity of a rug wherein the loops are formed in the weaving operation. It has been thought that if the loops were not separately 10 formed and stitched to the fabric base, they would pull out when the rug was in use and would, therefore, be unsatisfactory. In the present invention, the loops are secured firmly to the fabric base, while at the same time the staggered transverse relation of the loops prevents the spacing apart of the loops from causing the rug to be subject to "grinning." By reason of the fact that only a portion of the loops is drawn from the fabric in a picking operation, greater speed 15 and ease in picking back when a defect occurs during the tufting operation on the loom are possible since only a portion of the loops or tufts need be rearranged. The portion of the loops which is formed in a single picking operation 20 or step is such that each pair of loops transversely spaced apart from each other has at least one additional loop therebetween in a different transverse row. Thus, in the weaving of the rug, the chances of the loops back-twisting against 25 one another to form unsightly lumps of tufting is minimized. By the same token, the staggered transverse relation of the loops produces an upper body for the rug which is much more regular in appearance than would otherwise be 30 possible.

35 The invention is illustrated in the accompanying drawing, in which Fig. 1 is a fragmentary detail plan view of the rug with a portion of the upwardly-extending loops cut away immediately above the surface of the rug; and Fig. 2 is a fragmentary detail transverse sectional view taken along the line 2—2 of Fig. 1.

In the embodiment of the invention described herein, the rug is formed of pile warp threads 10, ground warp threads 11, and weft threads 12.

40 The weft or filling threads 12 and the ground warp threads 11 are preferably tightly twisted to form a sturdy tight body for gripping the pile warp threads therebetween. The pile warp threads 10, on the other hand, as illustrated, 45 are formed of a two-ply structure in which each ply is first slack-twisted and then brought together and over-twisted. The over-twisting substantially removes the slack twist of the individual plies and the resulting twisted pile warp

thread is bulky in appearance and relatively soft. This soft pile warp thread 10 is tightly gripped between the tightly and closely drawn weft threads 12 and ground warp threads 11.

Loops 13 are formed in the pile warp threads at spaced intervals by drawing the pile warp threads upwardly from the body of the fabric. Each of the loops 13 is preferably of a length greater than the distance by which the loop is spaced from the next adjacent loops formed in the same pile warp thread. By reason of the over-twist in the pile warp thread, the loops after being formed and released become twisted, as seen in the illustration.

Preferably, the loops which are formed in the pile warp thread are spaced apart from the next adjacent loops in the same pile warp thread by at least five weft threads. As shown, five weft threads may be disposed between each pair of loops and in the same pile warp thread, and an additional weft thread may extend between and beneath the two upwardly-extending strands or threads which form the loop.

Between each pair of pile warp threads, a pair of ground warp threads may be placed. As shown, one of the ground warp threads may be in the same shed with the pile warp threads, while the other ground warp thread may be in the opposite shed. With this construction, a weft thread passing transversely through and across the ground warp and pile warp threads passes over a ground warp thread, then under a ground warp thread and a pile warp thread, then over a ground warp thread, then under a ground warp thread and a pile warp thread, and so on.

In the forming of the loops in the rug, only a portion of the pile warp threads is drawn simultaneously from the fabric, preferably every third pile warp thread is formed into a loop in the picking operation. In the next loop-forming operation, another portion of the pile warp threads is drawn from the fabric. If in each case every third pile warp thread is drawn from the fabric to form a loop, after three loop-forming operations a second loop will be formed in each of the pile warp threads which was subjected to the first loop-forming or picking step. With this construction, the loops are not formed in straight transverse rows but, instead, are staggered transversely with respect to each other. When the fabric is folded or bent, the upper body of the rug does not separate transversely along the spaces between the loops as would be the case if the loops were drawn in straight transverse rows. By arranging the pile warp threads so that they are alternately drawn from the fabric in a plurality of different portions which are spaced between each other, a more regular body is provided for the rug, while at the same time the longitudinal spacing of the loops along each of the pile warp threads is sufficient to securely lock the loops to the fabric and prevent the loops from being pulled or drawn therefrom when the rug is in use.

By reason of the softness or loosely-woven character of the pile warp threads, the rug not only provides a more attractive appearance but also the pile warp threads cooperate with the tightly-drawn and twisted weft and ground warp threads to lock the pile warp threads against longitudinal movement under strain. Thus, when the rug is woven under tension, the weft threads and ground warp threads tightly engage the sides of the loops upon the release of tension so that the loops are prevented from being drawn from the fabric. Although the invention has been ill-

lustrated with the loops spaced apart longitudinally by five weft threads, it will be understood that seven weft threads between loops or a larger number of weft threads may, if desired, be used.

This application is a continuation-in-part of my co-pending application Serial No. 356,534 filed September 12, 1940 for Rug issued January 19, 1943 as Patent #2,308,577.

Although the invention has been described in connection with a specific embodiment, and specific structural details have been set forth for the purpose of illustrating the invention, it will be apparent that changes and modifications may be made without departing from the spirit and scope of the invention.

I claim:

1. A rug consisting essentially of ground warp and pile warp threads interwoven with weft threads, each of the pile warp threads being spaced apart from the next adjacent pile warp thread by at least one ground warp thread, the pile warp threads at spaced intervals being drawn from the fabric between a pair of weft threads to form upwardly-extending pile threads constituting the upper body of the rug, the pile threads extending upwardly a distance at least as great as the distance between the pile thread and the adjacent upwardly-extending pile thread of the same pile warp thread, each pile warp thread being drawn upwardly between a pair of weft threads different from the pair of weft threads between which the next adjacent pile warp thread is drawn.

2. A rug consisting essentially of ground warp and pile warp threads interwoven with weft threads, each of the pile warp threads being spaced apart from the next adjacent pile warp thread by at least one ground warp thread, each of the pile warp threads at spaced intervals thereof being drawn from the fabric between a pair of weft threads to form upwardly-extending pile threads constituting the upper body of the rug, a portion of the pile warp threads being drawn upwardly in a straight transverse row between a pair of weft threads and another portion of the pile warp threads being drawn upwardly between another pair of weft threads in a straight transverse row spaced from said first row, adjacent pile warp threads in each transverse row having therebetween a pile warp thread of another row.

3. A rug consisting essentially of ground warp and pile warp threads interwoven with weft threads, each of the pile warp threads being spaced apart from the next adjacent pile warp thread by at least one ground warp thread, the pile warp threads at spaced intervals being drawn from the woven fabric to form long spirally-twisted loops constituting the upper body of the rug, a portion of the pile warp threads being drawn upwardly in a straight transverse row between a pair of weft threads, and another portion of the pile warp threads being drawn upwardly in another straight transverse row spaced from said first row and between a different pair of weft threads, adjacent pile warp threads in each portion having therebetween a pile warp thread of the other portion.

4. A rug consisting essentially of ground and pile warp threads interwoven with weft threads, the pile warp threads being formed of over-twisted ply-yarn each of the plies of which is slack-twisted, each of the pile warp threads being spaced apart from the next adjacent pile warp threads by a pair of ground warp threads, one of

said pair of ground warp threads being in the same shed with the pile warp threads whereby the weft threads pass on the same side of the pile warp threads and one of the ground warp threads on the opposite side of the other of the pair of ground warp threads, the pile warp threads at spaced intervals being drawn from the woven fabric to form long spirally-twisted loops constituting the upper body of the rug, the loops being of greater length than the distance by which they are spaced apart, each loop being drawn upwardly between a pair of weft threads different from the pair of weft threads between which the loops of the next adjacent pile warp threads are drawn.

5. A rug consisting essentially of ground and pile warp threads interwoven with weft threads, the pile warp threads being formed of over-twisted ply-yarn each of the plies of which is slack-twisted, each of the pile warp threads being spaced apart from the next adjacent pile warp threads by a pair of ground warp threads, one of said pair of ground warp threads being in the same shed with the pile warp threads whereby the weft threads pass on the same side of the pile warp threads and one of the ground warp threads on the opposite side of the other of the pair of ground warp threads, the pile warp threads at spaced intervals being drawn from the woven fabric to form long spirally-twisted loops constituting the upper body of the rug, the loops being of greater length than the distance by which they are spaced apart, a portion of the pile

10 warp threads being drawn upwardly so that the loops thereof are formed in a straight transverse row between a pair of weft threads, and another portion of the pile warp threads being drawn upwardly so that the loops thereof are in another straight transverse row longitudinally spaced from said first row and between a different pair of weft threads, adjacent pile warp threads in each portion having therebetween a pile warp thread of the other portion.

15 6. A rug of the class set forth, consisting essentially of ground and pile warp threads interwoven with weft threads, the pile warp threads being formed of over-twisted ply-yarn, each of the plies of which is slack-twisted, each of the pile warp threads being spaced apart from the next adjacent pile warp threads by a pair of ground warp threads, one of said pair of ground warp threads being in the same shed with the pile

20 25 30 warp threads whereby the weft threads pass on the same side of the pile warp thread and one of the ground warp threads and on the opposite side of the other of the pair of ground warp threads, the pile warp threads at spaced intervals being drawn from the woven fabric to form long spirally-twisted loops constituting the upper body of the rug, the loops being of greater length than the distance by which they are spaced apart, each loop being drawn upwardly between two weft threads, one of said pair of ground warp threads passing over said two weft threads.
